3 Claims. (Cl. 48—118.5)

1

This invention relates to improvements in producer gas generators, particularly the type designed for installation on a motor vehicle. The objects of the invention are to produce a generator of simplified design which may be readily started and maintained in operation with better efficiency than has been heretofore possible.

In this construction the generator includes a combustion chamber having spaced sets of air tuyères with improved controlling means, curved grates placed in special relation to the tuyères, and a gas chamber, all constructed and arranged as shown in the accompanying specification and drawings. When mounted on the vehicle the generator is employed in association with a cooler, filter, mixing valve and fan mechanism, which will enable the operation to be started and maintained through appropriate control and regulation, all as hereinafter described.

In the drawings

Figure 1 is a vertical section through the form of generator when there are from one to four nozzles.

Figure 2 is a front elevation.

Figure 3 is a section on the line 3—3 of Figure 1.

Figure 4 is a fragmentary vertical section through the form of generator when there are five or more nozzles.

Figure 5 is an elevation of the same.

Figure 6 is a section on the line 6—6 of Figure 4.

Figure 7 is a diagrammatic view of all the apparatus when installed on a vehicle.

Figure 8 is an elevation of the gas cooler, partly in section.

Figure 9 is a vertical section through the filter.

Figure 10 is a section on the line 10—10 of Figure 9.

Figure 11 is an enlarged view, partly in section, of the air mixing valve.

Figure 12 is an enlarged view, partly in section, of the fan valve.

Referring to the drawings and first to the diagrammatic view in Figure 7, A indicates the generator from which the pipe 10 leads to the cooler B, connected by the pipe 11 with a filter C, connected by a pipe 12 with the mixing valve D, from which a pipe 13 leads to the fan control valve E, from which a pipe 14 leads to the fan F operated from the motor G, the fan having a suitable exhaust pipe 15. The fan control valve E has also a connecting pipe 16 leading to the exhaust manifold H of the engine.

In the form of generator shown in Figures 1 to 3, 17 indicates the combustion chamber, the upper portion 18 of which constitutes a hopper for the

2

fuel, being provided at the top with a removable cover 19 of suitable design which, when removed, will permit the fuel to be supplied to the hopper and generating chamber.

5 The lower part of the generating chamber constitutes a fire-pot 20 having at one side an inclined and curved grate 21, which is placed opposite a series of tuyères 22. These tuyères or nozzles 22 may be conveniently formed of cast iron 10 and set in the wall of the combustion chamber, the nozzle bore being carefully designed to suit the grate area and the depth of fuel bed for which the generator is designed. The tuyères or nozzles 22 are set in the wall of the combustion chamber 15 opposite and above the grates so that the draft through the fuel is diagonally downward. I have discovered that the shorter the fuel bed the smaller must the fuel be ground so that a more solid bed of fuel lie on the grate. The inclined arrangement of the grates having the nozzles set in a plane above permits the volatiles in the fuel being changed to fixed gases on their path downward through the incandescent fuel bed in the grates. The nozzle bore or air discharge opening 20 of each of the tuyères may be from $\frac{1}{8}$ " to $\frac{3}{4}$ " 25 diameter depending on the gas consumption of the unit on which the producer is installed and is fixed by the gas consumption required for idling so that 1800 degrees Fah. is maintained at the nozzles and 2800 degrees Fah. is maintained under 30 full load conditions.

The diameter required for any given engine is decided during test and can be increased by drilling while the unit is in operation. The nozzles are air cooled.

35 The inclined arrangement of the grate, which is shown in the drawings as being inclined upwardly at an average angle of about 45° to the horizontal from its lower edge to its uppermost portion and as having a correspondingly inclined and extending surface portion facing the discharge openings of the tuyères, permits a substantial fuel area to be provided while the curvature on the grate enables constant distance to be maintained between the tuyères and the grate area.

40 The fuel should be chosen to correspond with the depth of fuel which is maintained on the grate and should not be over $\frac{7}{8}$ " with fires left in. These sizes are governed to some extent by the quality of the fuel and may vary slightly from a good hard charcoal to a soft friable one.

45 The grate area is carefully designed in order to slow up the gas passing therethrough so that 50 the fuel will not be carried through the grate, and

in order that the temperature of the fuel body will range between 1800 degrees and 3000 degrees Fah. In order to obtain a low pressure drop the ratio of the size of the nozzle to the grate openings should not be less than about 8½ to 1, i. e. when the nozzle bore is ¾", the voids in the grate should not be less than 3¾" per nozzle, while the actual grate area should be 30 square inches.

The generating chamber itself may be formed of any suitable material. It will probably be found desirable to form the lower part of the chamber, including the fire box, of cast steel, while the upper portion may be formed of light gauge steel.

The admission of the air to the tuyères is controlled through an air chamber 23 mounted on the exterior of the generator, having separated rows of openings 24 and 25 controlled respectively by slide valves 26 and 27 slidably mounted on the air chamber and having openings corresponding to the openings 24 and 25. The openings 25 are directly opposite the openings in the tuyères 22 and are designed to be used when the generator is being started. After the generator is in operation these openings may be closed and the openings 24 opened, as hereinafter described which permits of regeneration or heating of the air supply to the nozzles.

The lower part of the fire box 29 is formed with a suitable clean-out door 28. Below and to one side of the grate 21 is a gas chamber 29 of substantial size having sufficient cubical contents to prevent pull over of small particles of scrubbers and also to allow of the preliminary cooling of the gas before entering the pipe 19. A clean-out door 30 is provided.

The construction of the cooler B is shown in Figure 8. It includes a plurality of tubes 31 opening into headers 32 and 33, the header 32 being divided by a partition 34 into an inlet chamber 35 and an outlet chamber 36. In this way the incoming gas will pass from the inlet chamber 35 through one section of the tubes 31 into the header 33 and thence through another section of the tubes through the outlet chamber 36. For convenience in cleaning the cooler, a water inlet pipe 37 may be connected to the header 33.

The filter C may be of any convenient design. In that shown it includes a cylindrical chamber 38, the lower part of which is filled with oil and the intermediate portion of which contains filtering material, such as excelsior, held between a perforated disc 39 and a spacer plate 41. The perforated disc 39 is connected to a sleeve 42, within which is mounted a screw threaded rod 40 extending through the handle 45, with which it has threaded engagement, the lower end of the threaded rod 40 being connected to a spacing element 46 of inverted U-shape, the lower end of which engages the bottom of the container 38 and the upper portion of which bears against the perforated disc 39. The spacer 41, the center portion of which may be formed with an aperture covered with wire mesh, is fixed in position on the sleeve 42. It will be thus seen that by turning the handle 45 the cover 43 may be tightened on the container, and if necessary the disc 39 may be drawn closer to the disc 41.

The construction of the mixing valve D is shown in Figure 11 of the drawings. It is designed to admit regulated quantities of air to the producer gas and is designed to be suitably controlled from the dashboard of the vehicle. It includes a plunger 48 reciprocable in the

perforated sleeve 49 mounted above a series of perforations 50 in the cylindrical base 51. The plunger will be operated by suitable mechanism from the dashboard of the vehicle so that it may be raised or lowered to expose varying numbers of the perforations in the sleeve 49 and thereby control the amount of air that is admitted to be mixed with the producer gas.

A convenient form of the control valve E is shown in Figure 12, in which a disc valve 52 controls the inlet port 53 from the pipe 13. When this disc valve is elevated, the gas may pass through the branch 54 to the pipe 14. When lowered the gas passes directly through the pipe 16 to the manifold H.

The general principle of operation of the apparatus is that the producer gas is formed in the generator A, cooled in the cooler and scrubber B and cleared in the filter C. Air is admitted to the gas in the mixing valve D, which is controlled from the dashboard. When starting, the motor G operates the suction fan F, which draws the air through the apparatus until gas is created in the generator. The fan exhausts through the pipe 15 and when the gas therefrom can be ignited, the gas is ready for ordinary operation and the engine is started in the usual manner after the valve E has been closed and the fan stopped.

The fires in the firebox are started through each of the openings 25 and the nozzles or tuyères 22 aligned therewith. Then the slide 27 is moved to cover these openings and the slide 26 is moved to open position to permit air to enter the chamber 23 through the openings 24. A more detailed outline of the operation and conditions to be observed in connection therewith may now be given.

Assuming that the gas generator is to be started cold for the first time, the fire chamber and hopper 18 are filled with charcoal, preferably crushed through a three-quarter inch screen and over a one-eighth inch screen, and free from dust. The slide 27 is moved to open the air intake openings 25, while the slide 26 is moved to close the openings 24. The air mixing valve D is closed and the valve E moved to position to permit the fan to draw the gas through to the exhaust pipe 15. The fan is set in operation, the charcoal is then ignited through the tuyères 22 by means of a lighter or paper torch. After about a minute the valve E is closed and the ignition of the engine turned on and the starter operated. At the same time the air mixing valve D is opened and the engine starts, whereupon it is adjusted to a proper operation of the engine and the slides 26 and 27 are adjusted to permit the air to be drawn through the openings 24.

The generation of gas in the producer is dependent upon the maintenance of a continuous draft of air into a glowing bed of fuel, this draft, when the generator is once started, being produced by the suction of the engine, which will be sufficient to maintain the draft after the combustion has been started in the fuel bed to the desired extent. If desired, the engine may be started on gasoline, the generator lighted, and with both the gas and gasoline throttles open the fire may be caused to maintain sufficient heat so that in a few minutes the gasoline may be shut off and the engine run on producer gas. It will be found that after the fuel in the generator has been ignited, the zone of incandescent fuel under the draft will rapidly increase until the

flowing mass extends from the nozzles to the conical grate. The actual reaction zone being some 3 to 3½ inches deep. This should take place in from sixty to ninety seconds.

It will be observed that the fire chamber is of the down-draft type, the air path through the fuel being generally downwardly. The oxygen which is contained in the air drawn into the fire zone through the tuyères 22 enters immediately into chemical combination with that portion of the fuel situated close to the nozzles and converts it to carbon dioxide, an inert and non-combustible gas. As this gas passes on through the incandescent bed of fuel towards the grate, the carbon dioxide is converted to carbon monoxide, which is the main constituent of the gas generated. Hydrogen is also present because of the hygroscopic character of the charcoal and of the presence of the moisture in the entering air. Generally speaking, the gas will contain about thirty per cent of carbon monoxide and about four per cent of hydrogen. Small percentages of methane and other hydrocarbon gases are also present.

Since the atmospheric air drawn into the generator contains almost eighty percent nitrogen by volume, which takes no part in the chemical reactions, the gas finally generated will contain about fifty percent of nitrogen. This nitrogen acts merely as a diluent and has no power value.

The temperature at which the reaction takes place should be from 1800 degrees F. to 2800 degrees F. the gas leaving the generator having a temperature of from 1300 to 1600 degrees F. which temperature must be reduced as close as possible to atmospheric temperature before being used in the engine. The gas leaves the generator at a relatively high speed, heavy ash being taken out in the chamber 29, and contains some impurities which are carried in suspension. As the gas enters the cooler B it is slowed down and cooled, certain of the heavier particles settling out of the same. Further reduction takes place in temperature as the gas passes through the filter C.

On leaving the filter the gas is mixed with air before entering the engine manifold by means of the air mixing valve D, which will be found to require little adjustment after having been once set correctly when the engine and generator have attained working heat. A mixture of producer gas and air in the best proportions to give maximum power when water vapor or steam is added to the fire, may contain as high as 75% of the heat units of an air gasoline mixture, consequently the power developed on producer gas seldom attains this figure, and ranges nearer fifty-five to sixty-two percent of the power developed on gasoline fuel. The power output of an engine using producer gas can be greatly increased by increasing the compression ratio to 8.25 to 1, this being the most useful compression ratio for producer gas, increasing the power some twenty-five to forty-five per cent. The spark should be advanced about 8 degrees when using producer gas. Producer gas will not detonate with compressions as high as 16 to 1.

It will be observed that the generator employs a plurality of separated nozzles, each of which will maintain separate reaction zones. The grate being curved, there will be a constant distance from each of these nozzles to the grate surface. It will be found possible, if desired, to use nozzles formed of cast iron, in which the fire or reaction zones are kept relatively small and are surrounded

by the cooler fuel. As many nozzles as desired may be used in the generator, the size of the opening being calculated to produce the horsepower required.

In the alternative form of the invention shown in Figures 4, 5 and 6 the generator A' is provided with a conical grate 60 supported on cross bars 61 and 62 in the lower section 63 of the generator, which constitutes a gas chamber and settling box, being provided at one side with a door 64 from which the settled material may be removed. Above this chamber is the fire box 65, having an upper hopper section 66 bolted thereto.

The tuyères or nozzles 66' are uniformly spaced around the section 65 and are surrounded on the outside by an air chamber 67 having a screened air inlet 68 and having a plurality of openings 69 opposite the tuyères which may be closed by a circular controlling member 70 mounted on the exterior of the air chamber with freedom to be turned on its axis in either direction. The screens 71 are provided for the openings 68 and may be adjustably held in position by thumb nuts and bolts 72 mounted on the outside of the air chamber 67.

The conical grate 60, disposed as shown in the drawings, provides as shown a grate surface portion inclined upwardly at an average angle of about 45° to the horizontal from the lower edge to the uppermost portion of the grate and facing the discharge openings of the tuyères, the surface portion being curved on a radius which is substantially equal to the distance from the discharge openings of the tuyères 66', so that the operation may be maintained as described with regard to the form of the invention shown in Figures 1 to 3.

Various modifications may be made in this invention without departing from the spirit thereof or the scope of the claims, and, therefore, the exact forms shown are to be taken as illustrative only and not in a limiting sense, and it is desired that only such limitations shall be placed thereon as are disclosed in the prior art or are set forth in the accompanying claims.

What I claim is:

1. A gas producer comprising a generator chamber having a vertical side wall, an air inlet tuyère mounted in said wall and having a discharge opening adjacent said wall within said chamber, and an inclined curved grate disposed in said chamber lower than said tuyère, said grate being inclined upwardly from a lower edge thereof at an angle of about 45° to the horizontal, thereby permitting a substantial fuel area to be provided, said grate being so curved that the cross section thereof in a vertical plane passing through said discharge opening and perpendicular to said grate is substantially in the form of an arc of a circle whose center is at said discharge opening, thereby providing for the maintenance of a diagonally downward path of substantially constant distance between the discharge opening and grate area.

2. A gas producer comprising a generator chamber having a vertical side wall, a row of air inlet tuyères mounted in a straight line in a horizontal plane in said wall, said tuyères having respective discharge openings therein adjacent said wall within said chamber and spaced to produce an exothermic reaction zone of substantial lateral extent, an inclined curved grate in said chamber and lower than said row of tuyères, and an outlet for product gases below said grate, said grate being inclined upwardly from a lower edge

thereof at an angle of about 45° to the horizontal, thereby permitting a substantial fuel area to be provided; said grate being so curved that the cross section thereof in a vertical plane passing through any one of said discharge openings and perpendicular to the surface of said grate is substantially in the form of an arc of a circle whose center is at said one of said discharge openings, thereby providing for the maintenance of a diagonally downward path between the discharge openings and grate area.

3. A gas producer comprising a generator chamber having a side wall in the form of a vertical cylinder, a row of spaced air inlet tuyères mounted in a horizontal plane in said wall; said tuyères having respective discharge openings adjacent said wall within said chamber; a grate having an inclined upper surface portion in said chamber lower than said row of tuyères and facing the latter, said grate being so shaped that a cross section thereof in a horizontal plane is substantially circular, and an outlet for product gases below said grate; said surface portion thereof extending inclined upwardly from the lower edge of said grate to the uppermost portion thereof at an average angle of about 45° to the horizontal, thereby permitting a substantial fuel area to be provided; said surface portion being so curved that the intersection thereof with a vertical plane perpendicular to said surface portion and passing through any one of said dis-

charge openings is substantially in the form of an arc of a circle whose center is at said one of said discharge openings, thereby providing for the maintenance of a diagonally downward path of substantially constant distance between said discharge openings and said grate.
